UNITED STATES PATENT OFFICE

S H HUNTER KUENZEL, OF KALAMAZOO, MICHIGAN, ASSIGNOR TO CHECKER CAB MANUFACTURING CORPORATION, OF KALAMAZOO, MICHIGAN

DESIGN FOR A VEHICLE LAMP HOUSING

Application filed January 15, 1931. Serial No. 38,314. Term of patent 7 years.

To all whom it may concern:

Be it known that I, S H HUNTER KUENZEL, a citizen of the United States, residing at the city and county of Kalamazoo, and State of Michigan, have invented a new, original, and ornamental Design for a Vehicle Lamp Housing, of which the following is a specification, reference being had to the accompanying drawings, forming part thereof.

Fig. 1 is a front elevational view of a lamp housing showing my new design, and

Fig. 2 is an end elevational view of the article shown in Fig. 1.

I claim:

The ornamental design for a vehicle lamp housing as shown.

S H HUNTER KUENZEL.
